Fig. 6.

FIGURE 1 is a front elevational view of a combined desk calendar and name plate showing my new design;

FIGURE 2 is a rear elevational view thereof;

FIGURE 3 is a top plan view thereof;

FIGURE 4 is a right elevational view thereof;

FIGURE 5 is a left elevational view thereof;

FIGURE 6 is a bottom plan view thereof.

The dominant features of my design shown in solid lines comprise a cardboard, triangular desk calendar having an interlocking ring locking means along its upper edge together with a leafed calendar pad on its front face and a nameplate representation on its rear face, the base

being longitudinally creased for convenience of folding, all as shown.

I claim:

The ornamental design for a combined desk calendar and name plate, substantially as shown and described.
